FIG.2.

FIG.1.

FIG.3.

FIG.4.

FIG.6.

INVENTOR:

ALBERT SCHWARTZ

ATTORNEY.

Charles W. Schwartz

UNITED STATES PATENT OFFICE.

ALBERT SCHWARTZ, OF NEW YORK, N. Y.

TELEPHONE.

Application filed January 21, 1927. Serial No. 162,592.

This invention relates to a novel device for silencing the voice of the speaker in telephone transmitters to prevent unauthorized persons from hearing a conversation.

5 This device is a sound deadening casing mounted over the telephone mouth-piece and is provided with an opening in front thereof of which closely fits the lips of the speaker.

One of the features of this invention relates to means for ventilating the sound deadening casing, when not in use, to the end that the device may be more sanitary and to completely eliminate the possibility of spreading disease. The ventilating means

15 may include easily controllable doors which while normally closed may be opened at intervals to permit a fresh current of air to circulate through the interior of the casing.

The doors themselves may act as fans when 20 quickly operated. When the doors are closed, however, the casing is practically airtight and since the mouth of the speaker closes the front opening it is impossible for the sound waves to escape to the exterior of the casing.

25 The present device is also suitable for use in noisy places, such as machine shops and busy streets, since no foreign noises may reach the vibrating membrane of the telephone transmitter.

30 It will be understood that the ventilating mechanism herein disclosed is only illustrative of the invention since the essence of the present invention is to ventilate a sound deadening casing by any means whatever.

35 Other features and advantages of this invention will hereinafter appear.

In the accompanying drawings;

Figure 1 is a cross-sectional view in elevation showing the device mounted on the diaphragm box of a standard telephone transmitter.

Figure 2 is a plan view, partly in cross-section, and shows the doors in operating or closed positions.

40 Figure 3 is a similar view, showing the doors in open or ventilating positions.

Figure 4 is a cross-sectional view through line 4—4 of Figure 2.

Figure 5 is a perspective view of the device mounted on the telephone transmitter.

Figure 6 is a cross-sectional view through line 6—6 of Figure 2.

In the form selected to better illustrate the present invention, the device consists of a sound deadening casing having an upper

double wall 10 and a lower double wall 11 both walls being secured to a square back plate 12, and to a front plate 13. The back plate is provided with a hole for receiving a mouth-piece 14 carried by a diaphragm box 60 15 of a telephone transmitter indicated generally by the numeral 16. The plate 12 is secured to a clamping piece 17 which engages, by means of prongs 18, the outer edge of a diaphragm front plate 19. This arrangement renders the casing easily detachable from the transmitter and may be manufactured and sold as a separate unit, independently of the telephone.

In order that a sound proof joint may be 70 provided between the clamping member 17 and the diaphragm plate 19 there is provided a ring 20 of rubber, felt or similar material. This ring may be forced into a recess formed at the inner edge of the clamping plate 17. 75

The front plate 13 has a hole therein which is provided with an edge 21 bent outwardly and designed to receive a mouth-piece formed by an inner wall 22 and an outer wall 23. The outer edge 24 of the mouth-piece is smooth and is shaped to conform with the lips of the speaker which serve as an effective closure to prevent emission of sound through the opening formed by the mouth-piece.

The sides of the casing are normally open as shown in Figure 3 so as to ventilate the interior thereof, but may be closed when the device is to be used by means of swiveled doors 25 and 26. The rear doors 26 are pivotally mounted on a rod 27 which is secured to the inner plates 28 of the upper and lower walls 10 and 11. The doors 25 are hinged on the free ends of the doors 26 by means of rods 29 which protrude through guiding slots 30 and are engaged by operating arms 31 under the control of a handle or finger piece 32. The arms 31 are provided with elongated slots 33 and are pivotally mounted by means of studs 34 and 35 between the plates of the lower wall 11. The stud 34 extends downwardly and carries, fast thereto, the finger piece 32. In order that both arms 31 may be concomitantly operated it is contrived to provide the arms with geared sectors having teeth 36 engaging with each other as shown in Figures 2 and 3. The free ends of the doors 25 are provided with pins 38 designed to slide in guiding slots 39 in the plate 28.

110

It will be understood that instead of providing the casing with side doors, the same could be provided with a single door at the top thereof. In this case the door could be operated by a single finger piece mounted at the end of a supporting shaft. The door could be made double, as in the form shown to illustrate this invention, thus further preventing the emission of sound through the walls to the exterior of the casing. The effect of a double wall is well known in the art.

Variations may be resorted to within the scope of the invention, and portions of the improvement may be used without others.

Having thus described my invention, I claim:

1. A sound deadening casing for a telephone transmitter having apertures at opposite sides thereof for permitting circulation of air therethrough, and manual means for concomitantly closing said apertures at will.

2. A sound deadening casing for a telephone transmitter having doors at the sides thereof for ventilating the interior of the casing, and manually controllable means for opening and closing said doors, said means including a pair of pivotally mounted geared

sectors for engaging said doors and a handle for operating one of the sectors.

3. A sound deadening casing for a telephone transmitter, said casing including a rigid frame, a mouth piece on said frame, means for attaching said frame to the diaphragm casing of the telephone transmitter, a pair of full sized doors at opposite sides of the casing, said doors serving as sound deadening walls when the apparatus is in use but being concomitantly operable to be opened at will so as to permit a current of air to circulate through the interior of the casing.

4. A sound deadening casing for a telephone transmitter, said casing including upper and lower walls, a front wall having a mouth-piece attached thereto, a rear wall having means for attaching the casing to the diaphragm casing of the telephone transmitter, a pair of doors forming the sides of the casing when the doors are closed, said doors being operable at will in a manner to leave a full sized opening at each side of the casing to thereby permit a current of air to circulate through the casing from one side to the other thereof.

In testimony whereof, I affix my signature.

ALBERT SCHWARTZ.
